FRANK P. MILLER, OF MEADVILLE, PENNSYLVANIA

TOOL HOLDER

Application filed October 11, 1926. Serial No. 140,875.

This invention relates to tool holders of the inserted blade type and an important object is to provide novel and reliable means whereby the blades are held in adjusted position against the thrust to which the same are subjected in use.

More specifically an object of the invention is to provide a simple arrangement by which the thrust on the blades is employed to more firmly hold the blades in place.

Other objects and advantages will be apparent during the course of the following description.

In the accompanying drawings forming a part of this application and in which like numerals are employed to designate like parts throughout the same:

Figure 1 is a fragmentary group perspective of the improved tool holder.

Figure 2 is a detail longitudinal sectional view through the cutter.

Figure 3 is a detail sectional view taken on line 3—3 of Figure 2.

Figure 4 is a fragmentary sectional perspective illustrating a slightly different mechanical expression of the invention.

Figure 5 is a similar view illustrating another mechanical expression of the invention.

Figure 6 is a detail sectional view illustrating a modification of the invention.

Figure 7 is a detail sectional view illustrating a slightly different form of invention.

Figure 8 is a similar view illustrating another modification of the invention.

Figure 9 is a detail sectional view illustrating a still further modification of the invention.

In the drawing the numeral 10 designates a carrier or body having a series of slots 11 for the reception of blades 12. Each blade has the inner edge or surface thereof engaged by a tapered wedge 14 so that the blade is driven outwardly into binding engagement

with the converging side walls of the slot as clearly shown in Figure 3.

Particular attention is invited to Figures 2 and 3 which illustrate that the wedge 14 is received in registering grooves 15 and 16 in the bottom wall of the slot and the inner edge of the blade. This arrangement holds

the wedge against lateral movement. Figure 2 clearly illustrates that the opposed active faces of the grooves 15 and 16 are inclined in the same general direction to intersect the line of thrust on the blade. The active face of the groove 16 extends at a greater angle to the line of thrust than does the active face of the groove 15. By this arrangement rearward movement of the wedge is inhibited by the inclination of the bottom wall of the groove 15 and rearward movement of the blade itself in response to the thrust thereon is resisted by the opposed active contacting faces of the groove 16 and the wedge.

For example, the angle of the active face of the groove 15 might be 3 degrees and the active face of the groove 16 might be 6 degrees. In such a case the included angle of the wedge 14 would be 3 degrees to cause the wedge to impart radial movement to the blade and thereby force the same into tight engagement with the walls of the slot.

Consideration of Figure 2 will clearly show that the bottom active face of the groove 15 extends at an angle to the line of thrust on the blade and therefore prevents the wedge from moving rearwardly in response to the thrust. Further consideration of this figure will show, that if the blade is to yield to the thrust it must ride up on the inclined face of the wedge 14. The interlocking connection between the blade and the carrier prevents this. In other words, the converging side walls of the slot and the blade will inhibit radial movement of the blade and since such radial movement is inhibited there can be no rearward movement of the blade.

In summarizing this phase of the invention it is pointed out that the active faces engaged by the wedge 14 slope in the same general direction, but at different angles to the line of thrust on the blade and in fact intersect the plane of the outer edge of the blade at a point rearwardly of the blade thereby producing a construction by which end thrust actually has the effect of more securely binding the blade and the wedge in their proper positions in the slot.

Figure 3 illustrates a practical means for holding the blade against outward radial

movement. As previously described the side-walls of the blade in this figure converge toward the periphery of the cutter. There are, however, other means by which the blade may be held against outward radial movement. For example, in Figure 4 I have shown one sidewall of the slot and the opposed face of the blade provided with a matching tongue and groove connection 18. It is believed to be obvious that such a tongue and groove connection holds the blade against outward radial movement and therefore performs the same mechanical function as the converging side-walls of the blade and the slot as shown in Figure 2.

Figure 5 illustrates that it is also possible to hold the blade against outward radial movement by the provision of grooves 19 in opposed sides of the slot and the blade to define a channel for the reception of a locking pin 20. It is thus apparent that any desirable mechanical means may be employed to hold the blade against outward radial movement.

In the forms of invention shown in Figures 1 to 5 inclusive, the wedge is introduced from the rear side of the cutter.

In the form shown in Figure 6 the wedge 24 is introduced from the forward or front side of the cutter and is intended to inhibit forward shifting of the blade 26 as a result of the thrust thereon. In this figure it is shown that the opposed active faces 27 and 28 of the blade and the slot respectively approach the plane of the outer edge of the blade in the same general direction, but at different angles to define a tapering socket for the reception of the wedge 24.

The different angles of the faces 27 and 28 hold the wedge and the blade against shifting in one direction in the same manner as does the construction shown in Figures 1 to 3 inclusive. The thrust in the other direction is, in this case, taken by a ring nut 29 threaded onto the body or carrier and engaged with the blade at the rear end thereof. It will be seen that the wedge 24 takes the thrust in one direction while the nut 29 takes the thrust in the other direction. However, it is entirely within the range of the invention to employ the nut 29 to supplement the action of the wedge 24 in taking the thrust in one direction only.

In the form of invention shown in Figure 7 the wedge 30 is introduced from the front of the cutter into the registering grooves 31 and 32 in the inner edge of the blade and the bottom of the slot respectively to inhibit rearward shifting of the blade. The active faces of the grooves 31 and 32 slope in the same general direction, but at slightly different angles and intersect the plane in which the outer edge of the blade is disposed to resist rearward movement of the blade. Notwithstanding the fact that the thrust is in the general direction of the taper of the wedge

the inclination of the active faces of the grooves 31 and 32 is such that the shifting of the blade is avoided.

In the form of invention illustrated in Figure 8 the blade 34 has the inner edge thereof provided with separate recesses 36 having active faces for engagement by the active faces of a pair of wedges 37 introduced from the rear side of the cutter. Grooves or recesses 38 cooperate with the recesses 36 in the formation of tapering sockets for the reception of the wedges 37. The double angle feature as described in the form of invention shown in Figures 1 to 3 inclusive is shown in Figure 8 and in explaining this it is pointed out that the active faces for engagement by each wedge extend in the same general direction, but at slightly different angles to the line of thrust to inhibit endwise shifting of the blade and the wedge. Figure 8 clearly illustrates that the pairs of opposed faces extend in opposite directions so that thrust from either direction is prevented from changing the position of the blade.

In the form of invention shown in Figure 9 the wedges 40 are introduced from opposite sides of the cutter and contact with separate pairs of opposed faces 41 and 42 in the blade and the carrier respectively. These active faces are in recesses in the blade and the cutter and approach the plane of the outer edge of the blade at slightly different angles to produce the peculiar binding action heretofore described in detail.

Of course, the sidewalks of the slots shown in Figures 7, 8, and 9 converge toward the periphery of the cutter to inhibit outward radial movement of the blades or any other means may be provided to inhibit such movement.

Having thus described the invention what is claimed is:

1. A rotary cutter comprising a body, a blade carried thereby, said blade and said body being provided with separate pairs of active faces approaching the plane of the outer edge of the blade in different directions, the faces of each pair being at slightly different angles, and separate wedges engaged with said pairs of faces.

2. A rotary cutter comprising a body, a blade carried thereby, said blade and said body being provided with separate pairs of active faces approaching the plane of the outer edge of the blade in different directions, the faces of each pair being at slightly different angles to each other and tilted in the same general direction, and separate wedges engaged with said pairs of faces and being introduced into the cutter from the same side.

3. A rotary cutter comprising a body, a blade carried thereby, said blade and said body being provided with separate pairs of active faces approaching the plane of the outer edge of the blade from opposite ends

of the blades, one face of one pair of faces being at an angle to the other face of that pair, and wedges engaged with said pairs of faces.

5 4. A cutter comprising a body having a slot, a blade in the slot, and a wedge between the blade and the bottom of the slot and having inner and outer bearing surfaces inclined outwardly in the same general direction with respect to the line in which the blade is prone to shift under the influence of the thrust thereon, there being means inhibiting outward movement of the blade, said blades and body having cooperating recesses to receive the wedges.

10 5. A cutter comprising a body having a slot, a blade in the slot, the bottom of the blade and the bottom of the slot being formed with opposed recesses, a wedge in said recesses, there being means to inhibit outward movement of the blade, said means cooperating with the wedge to inhibit endwise shifting of the blade.

15 6. A cutter comprising a body having a slot, a blade in the slot, the bottom of the blade and the bottom of the slot being formed with recesses, and a wedge in said recesses, there being means to inhibit outward movement of the blade, the inner and outer surfaces of the wedge being positioned to cooperate with the means to inhibit outward movement of the blade in resisting endwise shifting of the blade under the influence of the thrust thereon.

20 35 7. A cutter comprising a body having a slot provided with a bottom surface tilted outwardly toward one end, a wedge engaging said tilted bottom surface and having an outer surface tilted in the same general direction as the bottom surface of the slot, and a blade seating on said wedge, there being means inhibiting radial movement of the blade and thereby cooperating with the aforesaid tilted surfaces in resisting endwise shifting of the blade in one direction.

25 40 45 8. A cutter comprising a body having a slot provided with a bottom surface tilted outwardly toward the rear end of the body, a wedge engaged with said outwardly tilted bottom surface and having an outer surface tilted outwardly toward the rear end of the cutter, a blade engaged with the tilted outer surface of the wedge, there being means inhibiting radial movement of the blade and thereby cooperating with said outwardly tilted surfaces in resisting endwise shifting of the blade and the wedge in the same direction under influence of the blade thrust.

50 In testimony whereof I affix my signature.
FRANK P. MILLER.
